UNITED STATES PATENT OFFICE.

FREDERICK A. KOLSTER, OF WASHINGTON, DISTRICT OF COLUMBIA.

APPARATUS FOR TRANSMITTING RADIANT ENERGY.

1,394,560.

Specification of Letters Patent.

Patented Oct. 25, 1921.

Application filed November 27, 1916. Serial No. 133,520.

To all whom it may concern:

Be it known that I, FREDERICK A. KOLSTER, a citizen of the United States, residing at Washington, D. C., have invented a new 5 and useful Apparatus for Transmitting Radiant Energy, of which the following is a specification.

My invention relates to radio signaling or control systems involving the propagation 10 through the natural media of electro-radiant energy or electro-magnetic waves for telegraphy, telephony or any other signaling or control purposes.

My invention resides in apparatus for producing and impressing upon the natural media energy vibrating or alternating at 15 high frequency either in the form of sustained waves or waves in groups or wave trains, by recourse to structures and arrangements in which the disadvantageous effects 20 of the distributed inductance and distributed capacity, or either, of a transmitting antenna, as now commonly employed and comprising usually the open transmitting circuit, are overcome by employment as a radiating circuit one which is closed through 25 inductance and capacity, which is all substantially lumped or concentrated and in which the distributed capacity and distributed 30 inductance are each substantially *nil* and which, as a radiating circuit or path of oscillations for radiation purposes, lacks the usual high resistance of an antenna as commonly employed, and is therefore, in the 35 sense employed in the radio art, a circuit of low resistance.

Such a circuit preferably takes the form of a coil or winding of one or more turns or convolutions, which may be of any suitable 40 shape. Such a coil is connected through conductors of practically no distributed inductance or capacity with a capacity or condenser which forms a lumped or concentrated capacity as distinguished from the 45 distributed capacity of an ordinary antenna. In such a circuit the oscillations may be set up in any well known manner or they may be produced in a primary circuit and impressed by magnetic or capacitative coupling, or both, upon such closed circuit.

Furthermore, the physical dimensions of the apparatus are very small as compared with the antenna now commonly employed and the apparatus is relatively inexpensive 55 and will find its application not only for

high power long distance transmission, but also for portable transmitting apparatus, ship and lighthouse stations, moving vehicles such as automobiles, railroad trains and air craft, and particularly aeroplanes. 60

My invention resides further in apparatus for transmitting high frequency energy of the character referred to and reception thereof at a distant station by recourse to transmitting apparatus of the character 65 above described and receiving apparatus such, for example, as described in my prior Patent No. 1,311,654, July 29, 1919.

In such a system, even where the oscillations occur in groups or trains, as distinguished from sustained oscillation, they have so small a decrement that in effect they very closely approximate the conditions of sustained oscillations, with the result that at the receiving apparatus of like character 75 the selectivity, tuning or resonance is higher, sharper and better than in any system of which I am aware.

And in transmitting apparatus of the character herein described in which sustained oscillations are produced, by recourse to any suitable means, such as an electric arc, there results the advantage over the ordinary antenna that large amounts of energy may be transmitted without reinforcement of a certain harmonic or certain harmonics of the fundamental wave frequency, with the result that the oscillatory energy generated is practically completely transmitted at a given and fundamental 85 frequency. This is of decided advantage over the ordinary antenna transmitting system in that where sustained oscillations are employed, and particularly as produced by an electric arc, due to the distributed inductance and capacity of such antenna, a certain harmonic or certain harmonics of the fundamental frequency are reinforced, with the result that the effect and efficiency 90 of the transmitting apparatus as a whole 100 are diminished.

My invention resides further in apparatus for producing directive effects in transmission of electro-radiant energy.

For an understanding of my invention 105 and a description of some of the forms my apparatus may take, reference is to be had to the accompanying drawings, in which:

Figure 1 is a diagrammatic representation of transmitting apparatus comprising a 110

closed good radiating circuit inductively coupled with a closed persistently oscillating circuit.

Fig. 2 is a diagrammatic view of inductively coupled closed circuits of the general character referred to in connection with Fig. 1, but in which the capacity is of modified form for increasing or assisting radiation.

Fig. 3 is an arrangement similar to that in Fig. 2 in which, however, an arc is employed directly in the closed oscillating and radiating circuit for producing sustained oscillations therein.

Fig. 4 is an elementary perspective view illustrating a form my invention may take in which the inductance comprises two coils or windings whose planes are at an angle with respect to each other.

Fig. 5 is a diagrammatic view of transmitting and receiving apparatus employing the same inductance, which comprises two coils disposed at an angle with respect to each other.

Fig. 6 shows an elemental transmitting circuit in which a spark gap is connected directly in series with said circuit.

Fig. 7 shows a 2-coil closed transmitting circuit in which an arc is connected directly in series in said circuit.

Fig. 8 shows a modification suitable for directive effects.

Referring to Fig. 1, A is a coil or winding of rectangular or any other suitable shape. It preferably consists of a plurality of convolutions or turns of wire or conductor. The arrangement may be such that the axial length of the coil A is very short as compared with its diameter, though my invention is not limited thereto. The conductor may be of any suitable material, and is preferably litzendraht or high frequency cable, though it may be solid copper or other wire, or copper or other tube. The coil A is connected in a closed circuit in series with the capacity or condenser C, which may be adjustable, and the adjustable secondary s of an oscillation transformer whose adjustable primary p is connected in closed circuit with an adjustable condenser or capacity C₁, and a spark gap g, which may be of the single gap type, as illustrated, or may be of any other suitable type. To the terminals of the gap g are connected the terminals of the high tension secondary S of a transformer T whose primary P is connected in circuit with a suitable source of current G, such as a source of alternating current, and a key or other signaling or controlling instrument k.

When the key k is closed the transformer T is energized and its secondary S charges the condenser C₁ to a high potential which breaks down the gap g with resultant high frequency oscillations in the circuit g, p, C₁, whose frequency is dependent upon the capacity of the condenser C₁ and the inductance of the primary p.

These oscillations are then impressed upon the closed persistent radiating circuit due to the inductive coupling between the primary p and secondary s of the oscillation transformer. The secondary or closed radiating circuit may then be suitably tuned to the frequency of the oscillations generated in the primary circuit, and there will then be set up in the closed radiating circuit oscillations, with the result that the coil A radiates into space energy of like frequency. In such an arrangement substantially all of the radiation takes place from the coil A, which is in effect the radiating element of the system. The radiating element A is also a directive radiator in that the intensity of radiation is greatest in the plane of the coil, and is less in other directions.

Or the closed primary and secondary circuits may be detuned with respect to each other, especially when other types of spark gap are used, as for example, a quench gap, all in well known manner.

In any event, the radiating circuit including the coil A is of low resistance, especially in the sense employed in the radio art regarding antennae of the open type. Its inductance is substantially completely lumped or concentrated, that is, its distributed inductance is practically nil. The same is true as to its capacity as produced by the condenser C. Accordingly the structure is such that the ideal of an oscillation circuit is very closely approximated. Even when the oscillations are in groups or trains, as they are when employing a spark gap as described, the amplitudes of successive waves in a train or group differ but slightly from each other, that is, the decrement is extremely small.

By way of example merely, and without limiting my invention thereto, it may be stated that with a transmitting apparatus such as shown in Fig. 1 and employing only 100 watts at 6 amperes in the closed radiating circuit including the coil A, I have transmitted radio telegraphic signals over eighteen and a half miles of wooded country to a receiving apparatus of the character described in connection with Fig. 5 herein, that is, employing two coils whose planes are at an angle with each other, the coil A at the transmitting station being of four convolutions and twelve feet square, while each of the coils A and B at the receiving end was only four feet square.

In Fig. 2 the arrangement is substantially the same as that described in connection with Fig. 1, except that the condenser C is composed of the two capacity areas K and K₁, neither of which, however, need be elevated or requires much room or space. These capacity areas are shown as plates, but may be of any other suitable structure, and one of them, as K₁, may be connected to earth E_a.

by closing the switch *sw*, though it will be understood that of all the closed radiating circuits herein described they may be completely isolated from earth.

- 5 In this arrangement which also is capable of directing radiation the capacity of the closed radiating circuit is procured by a structure which assists in radiation in that the larger separated capacity areas assist in 10 radiating or augmenting the electrostatic component of the electro-radiant energy, while the coil *A* is largely concerned only with the magnetic component.

Due to their relatively great size, as compared with an ordinary condenser like *C* of Fig. 1, the areas *K* and *K*₁ will, generally be fixed and therefore their capacity is substantially constant. To procure variable capacity in the closed radiating circuit including the coil *A* there may be connected in parallel to the condenser formed by the areas *K* and *K*₁ a variable condenser *C*₂ which may be brought into circuit by closing the switch *f*. Then by varying the condenser *C*₂ the total capacity of the radiating circuit may be varied for well known purposes, such as tuning or adjustment of wave length.

In Fig. 3, a structure is shown similar to that of Fig. 2 in that the capacity areas *K* and *K*₁ are employed, as well as a condenser *C*₂ if desired. Here again the capacity area *K*₁ may be connected to earth *Ea* through switch *sw*. But the purpose of this figure is to illustrate the use in series in such a closed radiating circuit of an electric arc *D* such as employed in now well known arc transmitting sets, the energy being supplied to the arc *D* in well known manner from a circuit whose conductors are indicated at *h* and *i*. 10 In series in the closed radiating circuit is shown a small additional lumped inductance *e* in shunt to which is connected the key or other signaling device *k*. In operation, as is well understood in the art, the arc *D* will set up sustained oscillations in the closed radiating circuit and their frequency will be determined by the capacity and inductance of that circuit. By pressing the key *k* the amount of inductance of the circuit is changed and 15 the frequency of the oscillations is correspondingly changed and at such changed value produces dot, dash or other code or signal characters.

By using with the arc a closed radiating circuit as described, whose distributed inductance and capacity are each substantially *nil*, reinforcement of a harmonic of the fundamental oscillation frequency will not occur, as in the case of an ordinary antenna 20 which has perforce distributed inductance and capacity.

In place of using a single coil *A* in the closed radiating circuit, a plurality of such coils may be employed with their planes disposed at angles with respect to each other.

In Fig. 4 is shown such an arrangement in which two coils are employed, *A*, *B*, disposed at an angle with respect to each other, and rotatable about their vertical axis *a*. With the graduated arc or scale *c* co-operates 70 the pointer *b* movable with the coils *A* and *B*. When the coils *A* and *B* are used in transmitting, as explained in connection with Fig. 5, directive effect is procured by rotating the coils *A*, *B* to such position that the pointer 75 points toward the receiving station, as *S*₂, toward which the energy will be radiated more powerfully than in other directions, as for example, toward the station *S*₁. And when the coils *A*, *B* are used for receiving, as explained in connection with Fig. 5 and in my said prior application Serial Number 87,914, directive reception effects are procured by 80 rotating the coils *A*, *B* to such position that the pointer *b* points toward the station, as *S*₂, from which a message is to be received.

One mode of use of such coils is shown in Fig. 5, where they are connected in series with each other and to the terminals *j* and *m* of a double throw switch *n*, which in the 90 position indicated connects the terminals *j*, *m* to the terminals *o* and *q*, respectively, and so includes in series with the coils *A*, *B* the adjustable condenser *C* and the adjustable secondary *s* of an oscillation transformer whose primary *p* is connected in series with the adjustable condenser *C*, and the arc *D* to which current is supplied by the conductors *h* and *i*. In shunt to part of the secondary *s* is connected the key *k* for 100 changing the wave length, as described in connection with Fig. 3.

When it is desired to receive a message the switch *n* is thrown over into its other position, whereby it connects the terminals *j* and *m* with the terminals *r* and *t* of a closed circuit including the adjustable receiving condenser *C*₃ and the primary *p*₁ of an oscillation transformer whose secondary *s*₁ is bridged by the adjustable condenser *C*₄ in 110 circuit with which are connected the adjustable condenser *C*₅, as a stop condenser, and any suitable wave detecting device, as for example, an audion *E* comprising the plate electrode *u*, grid *v*, and incandescent 115 filament *w* energized from the battery *x*. In circuit with the high tension battery *y* is connected the telephone receiver *z*.

By using at both stations transmitting and receiving apparatus such as shown in Fig. 5, we have a system in which at the transmitter there is a closed good radiating circuit whose dimensions are small and whose distributed inductance and capacity are substantially *nil*, and at the receiving 120 station a closed good absorbing circuit, also of small dimensions, and whose distributed capacity and inductance are substantially *nil*, there being two closed circuits, primary and secondary, at the transmitting station, 125 130

and two closed circuits, primary and secondary, at the receiving station, though it will be understood that any apparatus of the character herein described may be employed to transmit to apparatus of any suitable type at the receiving station.

Where two closed circuits are employed at each station, as described, there is produced a very effective system whose selectivity is extremely high, due to the fact that the transmitted waves have extremely small damping, even if transmitted in groups or trains, and are received in an absorption system which is highly selective because of its low resistance and the lack of distributed capacity and inductance in the absorbing circuit.

And obviously there is the additional advantage in such a system, as described in my Patent No. 1311654, of the prevention of interference and static disturbances, and direction finding.

In Fig. 6 is shown a spark gap g directly in series in the closed radiating circuit including also the coil A and the condenser C, and in such respect is analogous to Fig. 3, where the arc D is inserted directly in series in the closed radiating circuit.

In Fig. 7 there is shown an arc D directly in series in the radiating circuit comprising in this instance the two coils A and B disposed at an angle with respect to each other. Obviously in place of the arc D there may be used a spark gap g , as in Fig. 6.

Directive effect in transmission, that is, radiation of greater intensity in one direction than in other directions, is produced by all the forms of apparatus herein illustrated.

More decided directive effect in transmission may be procured by apparatus of the general character illustrated in Fig. 8 wherein the capacity areas K , K_1 , forming the condenser C, are long and low, the length extending in the direction in which the signals or energy are to be radiated. In circuit with the condenser C is shown the coil A which also may be long and low, its length extending in the direction in which the signals are to be sent or radiated. While in Fig. 8 I have shown both the condenser and the coil long and low, it is to be understood that either of them may be long and low and the other take any suitable form.

It will be understood as to all the forms of radiating and absorbing circuits herein described that they are of low resistance, in the high frequency sense, and their distributed capacity and distributed inductance are each substantially *nil*, thus approaching very closely the ideal for oscillatory circuits, and in consequence may be of relatively small physical dimensions, correspondingly inexpensive to manu-

facture, and in fact gaining certain advantages lost in the ordinary open antenna systems due to the distributed capacity, distributed inductance and relatively high resistance thereof.

And as hereinbefore intimated the closed radiating circuit may be entirely isolated from earth or may be connected to earth, as by connecting one plate or armature of the condenser or capacity thereof to earth E_a through switch sw , or by making earth connection to any other suitable point or points in the circuit.

Obviously a plurality of windings A and B may be used in any of the relations where winding A only is shown; and vice versa, where windings A and B are shown, they may be supplanted by winding A only.

For purposes of radio telephony a telephone transmitter or telephone transmitting apparatus may be associated with the transmitting apparatus herein described in any of the manners well understood in connection with radio telephony as heretofore practised with ordinary antenna radiators.

What I claim is:

1. A radiator comprising a closed radiating circuit, an inductance in said circuit, and a capacity in said circuit comprising large separated areas, said capacity areas and said inductance serving as radiating elements, the distributed capacity and inductance of said circuit being substantially *nil*.

2. Transmitting apparatus comprising a closed radiating circuit, lumped inductance in said circuit, capacity in said circuit, and an electric arc connected in series in said circuit, the distributed capacity and inductance of said circuit being substantially *nil*.

3. Transmitting apparatus comprising a closed radiating circuit, lumped inductance in said circuit, a capacity in said circuit comprising large separated capacity areas, said capacity areas and said inductance serving as radiating elements, and a condenser connected in parallel with the condenser formed by said capacity areas.

4. Radio apparatus comprising an inductance coil having a plurality of turns, a capacity area external to and separate from said coil, and a connection from said coil to said capacity area, said coil and said capacity area each co-acting directly with a natural medium for exchange of high frequency energy therebetween.

5. Radio apparatus comprising a rotatable inductance coil having a plurality of turns, a capacity area external to and separate from said coil, and a connection from said coil to said capacity area, said coil and said capacity area each co-acting directly with a natural medium for exchange of high frequency energy therebetween.

6. Radio apparatus comprising an axially

short inductance coil consisting of a plurality of turns, a capacity area external to and separate from said coil, a condenser in circuit with said coil, and a connection from said coil to said capacity area, said coil and said capacity area each co-acting directly with a natural medium for exchange of high frequency energy therebetween.

7. Radio apparatus comprising a rotatable 10 axially short inductance coil consisting of a plurality of turns, a capacity area external to and separate from said coil, a variable condenser in circuit with said coil, and a connection from said coil to said capacity area, 15 said coil and said capacity area each co-acting directly with a natural medium for exchange of high frequency energy therebetween.

8. Apparatus for impressing electro-radiant 20 energy upon the natural media, comprising a closed radiating circuit including capacity and a radiating inductance, said capacity comprising a radiating capacity area.

9. Apparatus for impressing electro-radiant 25 energy upon the natural media, comprising a closed radiating circuit including capacity and a radiating inductance, said capacity comprising a radiating capacity area aligned with said radiating inductance.

10. Apparatus for impressing electro-radiant 30 energy upon the natural media, comprising a closed radiating circuit including capacity and a radiating inductance, said capacity comprising a radiating capacity area, 35 the distributed capacity and inductance of said radiating circuit being very small.

11. Apparatus for impressing electro-radiant 40 energy upon the natural media, comprising a closed radiating circuit including capacity and a radiating inductance, said capacity comprising a radiating capacity area, and a source of oscillations in said radiating circuit.

12. Apparatus for impressing electro-radiant 45 energy upon the natural media, comprising a closed radiating circuit including capacity and a radiating inductance, said capacity comprising a radiating capacity area, and a source of sustained oscillations in said 50 radiating circuit.

13. Transmitting apparatus comprising a closed radiating circuit, a source of oscillations in said circuit, a capacity and a radiating inductance coil in said circuit, said 55 capacity comprising a radiating capacity area, the distributed capacity and inductance of said radiating circuit being very small.

14. Transmitting apparatus comprising a closed radiating circuit, an arc in said circuit, a capacity and a radiating inductance coil in said circuit, said capacity comprising a radiating capacity area, the distributed 60 capacity and inductance of said radiating circuit being very small.

15. Transmitting apparatus comprising a 65 closed radiating circuit, a plurality of capacities in said circuit, a radiating inductance coil in said circuit, one of said capacities comprising a radiating capacity area.

16. Transmitting apparatus comprising a 70 closed radiating circuit, a plurality of capacities in parallel with each other in said circuit, a radiating inductance coil in said circuit, one of said capacities comprising a radiating capacity area. 75

17. Transmitting apparatus comprising a closed radiating circuit, a plurality of capacities in said circuit, one of said capacities being variable, another of said capacities comprising a radiating capacity area, and a 80 radiating inductance coil in said circuit.

18. Transmitting apparatus comprising a closed radiating circuit, a radiating inductance coil in said circuit, a capacity in said circuit comprising a radiating capacity area, 85 and an earth connection to said capacity.

19. Transmitting apparatus comprising a closed radiating circuit, a radiating inductance coil in said circuit, a capacity in said circuit comprising a radiating capacity area, 90 and a connection to earth from an armature of said capacity.

20. Apparatus for impressing electro-radiant 95 energy upon the natural media, comprising a closed radiating circuit including a capacity and a radiating inductance, said capacity comprising a radiating capacity area, and means for varying the inductance of said circuit.

21. Apparatus for impressing electro-radiant 100 energy upon the natural media, comprising a closed radiating circuit including capacity and a radiating inductance, said capacity comprising a radiating capacity area, and means for varying the capacity of 105 said circuit.

22. Apparatus for impressing electro-radiant 110 energy upon the natural media, comprising a closed radiating circuit including capacity and a radiating inductance, said capacity comprising a radiating capacity area, and means for varying the capacity and inductance of said circuit.

23. Transmitting apparatus comprising a closed radiating circuit, a radiating inductance coil in said circuit disposed with its plane substantially vertical, and a capacity in said circuit, said capacity comprising a radiating capacity area. 115

24. Transmitting apparatus comprising a 120 closed radiating circuit, a radiating inductance coil in said circuit disposed with its plane substantially vertical, and a capacity in said circuit, said capacity comprising a substantially horizontal radiating capacity 125 area.

25. Transmitting apparatus comprising a closed radiating circuit, a plurality of radi-

ating inductance coils in said circuit, and capacity in said circuit, said capacity comprising a radiating capacity area.

26. Transmitting apparatus comprising a closed radiating circuit, a plurality of radiating inductance coils in said circuit, and capacity in said circuit, said capacity comprising a radiating capacity area, said coils having their planes disposed at an angle with respect to each other.
27. Transmitting apparatus comprising a closed radiating circuit, an axially short radiating inductance coil in said circuit having a plurality of turns and of dimensions small compared with the length of the radiated wave, and capacity in said circuit, said capacity comprising a radiating capacity area.
28. Transmitting apparatus comprising a closed radiating circuit, an axially short radiating inductance coil in said circuit having a plurality of turns disposed in a vertical plane and of dimensions small compared with the length of the radiated wave, and capacity in said circuit, said capacity comprising a radiating capacity area.

In testimony whereof I have hereunto affixed my signature this 24th day of November, 1916.

FREDERICK A. KOLSTER.
